UNITED STATES PATENT OFFICE.

ANTONIO NARDEI, OF DELMONT, PENNSYLVANIA.

DESIGN FOR A TABLE TOP.

Application filed February 19, 1925. Serial No. 12,423. Term of patent 7 years.

To all whom it may concern:

Be it known that I, ANTONIO NARDEI, a citizen of the United States, residing at Delmont, in the county of Westmoreland and State of Pennsylvania, have invented a new, original, and ornamental Design for Table Tops, of which the following is a specification, reference being had to the accompanying drawing, forming part thereof.

I claim:

The ornamental design for a table top, as shown.

ANTONIO NARDEI.
